PAVEMENT CONSTRUCTION

Harry N. Sandell, Boston, Mass.

Application April 22, 1937, Serial No. 138,303

3 Claims. (Cl. 94—18)

This invention relates to a concrete pavement construction and to the method of applying an expansion joint to adjacent spaced apart sections thereof.

5 In many concrete structures and particularly in concrete pavements it is necessary to provide expansion joints at regular intervals to allow for seasonal expansion and contraction of the structures. Many expansion joints heretofore utilized have proved unsatisfactory for various reasons. In certain instances the expansion of the concrete pavement causes ridges to be formed at the joints, which is objectionable. In other instances the joints are too complicated and expensive and not easily insertable in the concrete when the latter is poured, and the cost of the roadway is consequently excessive. In still other instances the joints do not effectively waterproof the structure.

10 The primary object of this invention is to provide an improved concrete slab or pavement construction wherein an inexpensive type of reinforced, flexible, waterproof material may be easily and quickly applied to adjacent sections of concrete when the latter is poured in a manner to constitute an effective waterproof expansion joint without interfering with and delaying construction or materially increasing the cost of the roadway.

15 Another object of the invention is to provide an improved construction wherein the space between the concrete sections is effectively waterproofed to exclude moisture therefrom notwithstanding seasonal temperature changes and consequent movement caused by the expansion and contraction of the various materials utilized which often have different co-efficients of expansion.

20 Still another object of the invention is to provide a construction wherein the amount of plastic filling material required to seal the upper portion of the space between adjacent concrete slabs is reduced to a minimum, thereby reducing the amount of said filling material that may be squeezed from said space when the concrete expands and preventing the formation of ridges in the roadway at the joints.

25 The invention consists in a pavement construction and method of applying an expansion joint thereto as set forth in the following specification and particularly as pointed out in the claims thereof.

30 Referring to the drawing:

35 Fig. 1 is an isometric view illustrating the method of assembling an expansion joint for a

pavement construction embodying my invention, prior to the pouring of the concrete.

Fig. 2 is a vertical section through the adjacent end portions of two concrete slabs and intervening expansion joint of a pavement construction embodying the invention.

Fig. 3 is a plan view of a portion of a strip of flexible waterproof sheet material utilized in the pavement construction of this invention.

Fig. 4 is a detail transverse sectional view of the retaining member as taken on the line 4—4 of Fig. 1.

Like numerals refer to like parts throughout the several views of the drawing.

In the drawing, 4 represents a roadbed, or like surface, and 5 represents an inverted T shaped spacing member resting thereon and secured at any location where it is desirable to provide an expansion joint between the adjacent concrete slabs of a pavement or roadway. The spacing member 5 is formed of suitable sheet metal, and may be of any length desired. It has a flat horizontal base portion 6 embodied therein which is bent and folded upon itself to provide oppositely extending horizontal flange portions 7 adapted to rest upon the roadbed 4, and said spacing member is secured to the roadbed 4 by means of suitable spikes 8 which are driven through openings provided therefor in said flange portions and into said roadbed. The sheet material of the spacing member 5 is furthermore bent upwardly from the base portion 6 to provide relatively parallel, vertical side walls 9 spaced one from the other a distance it is desired shall intervene between the lower portions of the adjacent concrete slabs 10 of the finished pavement.

30 Located in the spacing member 5 upon the base portion 6 thereof and between the side walls 9 thereof is a filler 11 preferably consisting of a compressible fibrous material as, for example, a compressible fibre board of sufficient thickness to substantially fill the space between the side walls 9, and said fibre board may extend above the top edges of said side walls, if it is so desired, and constitute a supporting means for a reinforced, flexible, waterproof material 12, illustrated in detail in Fig. 3. The fibrous filler material 11 must be of sufficient stability to firmly support the material 12 and also hold the side walls 9 correctly spaced when the concrete 10 is poured, and at the same time be sufficiently compressible to permit the concrete slabs to expand toward each other, at which time the side walls 9 of the spacing member 5 will also be forced toward each other. Under certain con-

ditions it may not be necessary for the filler material to project above the top edges of the side walls 9, in which event the flexible material 12 may rest upon and be supported by said side walls.

The flexible material 12 utilized in the pavement construction of this invention may be utilized for various purposes and at numerous locations in masonry structures and has been made 10 the subject matter of a co-pending application, Serial No. 103,257, and of a Patent No. 2,017,106, dated October 15, 1935. Briefly described, this material consists of outer layers of a strong waterpoofed textile fabric 13 having a metal reinforcing material, preferably a wire fabric 14, located therebetween and embedded in a layer of plastic asphalt 15 also interposed between the layers of textile fabric 13. The wire fabric 14 projects outwardly a suitable distance beyond 15 the opposite edges of the textile fabric 13 to provide anchoring portions which are eventually embedded in the concrete as will be hereinafter more fully described. The material 13 in strips of suitable length and width is placed upon the 20 filler 11 or upon the top edges of the side walls 9, if circumstances permit, and is folded downwardly against said side walls as illustrated in Fig. 1 of the drawing. A channel shaped retaining member 16 provided with parallel side walls 25 17 is then applied to the sheet material 12 as illustrated in Fig. 1 to hold said sheet material firmly against the side walls 9. Spacing members 18 secured to the under surface of the retaining member 16 between the side walls 17 thereof rest 30 upon the uppermost portion of the strip of flexible material 12, thereby positioning the top surface of said retaining member a predetermined distance above said material 12 and at a location which has been determined shall be the 35 level of the top surface of the finished pavement. After the retaining member 16 has been positioned upon the material 12 the opposite edge portions of said material which project below the lower edge portions of the side walls 17 of the retaining member 16 are bent upwardly to 40 a horizontal position against said lower edge portions as illustrated in Fig. 1 and it is evident that the lower edges of the side walls 17 determine the location at which the edge portions of the material 12 shall be embedded in the concrete 45 of the finished pavement.

The concrete is now applied to the roadbed 4 to the height of the top surface of the retaining member 16 and the opposite edge portions of the 50 flexible material which project from beneath the lower edges of the side walls 17 of said retaining member 16 are embedded in the concrete slabs 10 and firmly anchored therein by means of the exposed wire fabric 14. The portion of the waterpoofed textile fabric 13 which is also embedded in the concrete 10 provides an effective watertight bond with said concrete.

After the concrete has set, the retaining member 16 is removed and the resulting vacant space 55 is filled with temporarily liquid asphalt, or equivalent material 19, in a well-known manner to complete the sealing of the joint to exclude water therefrom.

In operation, as the concrete slabs 10 expand 60 toward each other, the filler materials 11 and 19 will be compressed and the side walls 9 of the spacing member 5 and upstanding portions of the reinforced sheet material 12 will be forced

toward each other. A small quantity of the filler material 19 will be forced upwardly from between the concrete slabs 10, but the amount will be negligible. Movement transmitted from the concrete slabs 10 to the flexible material 12 5 resulting from temperature changes, or roadway vibrations, is effectively dissipated by the wire fabric 14 which constitutes a reinforcing means for said material 12, and fracturing of the material is thereby prevented. The various elements constituting the joint are all inexpensive and easily installed and the joint will effectively exclude water indefinitely from beneath the adjacent end portions of the concrete slabs 10. Small stones will be prevented from entering 15 the space between the concrete slabs from below by the spacing member 5 and only a very small quantity of filling material 19 is required to fill the space at the upper portion of the joint.

Although I have described the flexible waterproof material 12 as being folded downwardly against the side walls 9 of the spacing member 5 during assembly, and the opposite edge portions of said material as being bent upwardly against the lower edges of the retaining member 16 after the latter has been positioned upon said sheet material, it is evident that the sheet material may be bent into its proper form before being assembled if it is so desired.

I claim:

1. In a masonry structure the combination with concrete and like slabs of an inverted T shaped spacing member for said slabs interposed therebetween having a vertically disposed compressible portion embodied therein, a strip of reinforced waterproof fabric positioned astride said compressible portion of said spacing member and having oppositely projecting metallic anchoring portions embedded in said concrete slabs, and a filler in the space between the concrete slabs 40 above the waterproof material.

2. In a masonry structure the combination with concrete and like slabs of an inverted T shaped spacing member for said slabs interposed therebetween having vertical side walls embodied 45 therein, a compressible fibrous filler permanently interposed between said side walls, a flexible waterproof fabric positioned astride said spacing member and folded downwardly against said side walls and having oppositely projecting anchoring portions embedded in said slabs, and a filler in the space between the concrete slabs above the waterproof material.

3. In a masonry structure the combination with concrete and like slabs of an inverted T shaped 55 spacing member for said slabs interposed therebetween having vertical side walls embodied therein, a compressible fibrous filler interposed between said side walls, a strip of reinforced waterproof fabric positioned astride said spacing member and having oppositely projecting metallic anchoring portions embedded in said slabs, means to determine the vertical position of said anchoring portions in the concrete slabs and to hold said flexible material positioned against the 60 side walls during the pouring of the concrete, and a filler in the space between the concrete slabs above the waterproof material after the last-named means has been removed from between said slabs.

HARRY N. SANDELL.
